DESIGN FOR A HEAT CONTROL AND INDICATOR PANEL FOR RANGES OR THE LIKE

Carl G. Björncrantz, Evanston, Ill., assignor to
Florence Stove Company, Gardner, Mass., a
corporation of Massachusetts

Application March 29, 1945, Serial No. 118,763

Term of patent 7 years

(CL. D81—25)

To all whom it may concern:

Be it known that I, Carl G. Björncrantz, a citizen of the United States, residing at Evanston, in the county of Cook and State of Illinois, have invented a new, original, and ornamental Design for a Heat Control and Indicator Panel for Ranges or the like, of which the following is a specification, reference being had to the accompanying drawing, forming a part thereof.

Figure 1 is a top plan view of a heat control and indicator panel for ranges or the like showing my new design;

Fig. 2 is a front elevational view thereof; and
Fig. 3 is an end elevational view thereof.

The dominant features of the design reside in
the portions shown in full lines in the drawing.

I claim:

The ornamental design for a heat control and
indicator panel for ranges or the like, substantially
as shown and described.

CARL G. BJÖRNCRANTZ.
